CLAIM

The ornamental design for a golf fairway wood head, as shown and described.

DESCRIPTION

FIG. 1 is a top perspective view of the golf fairway wood head;

FIG. 2 is a bottom perspective view of the golf fairway wood head of FIG. 1;

FIG. 3 is a front elevational view of the golf fairway wood head of FIG. 1;

FIG. 4 is a rear elevational view of the golf fairway wood head of FIG. 1;

FIG. 5 is a top view of the golf fairway wood head of FIG. 1;

FIG. 6 is a bottom view of the golf fairway wood head of FIG. 1;

FIG. 7 is a heel end view of the golf fairway wood head of FIG. 1; and,

FIG. 8 is a toe end view of the golf fairway wood head of FIG. 1.

The broken lines shown in FIGS. 1, 3, 5, 7, and 8 are for illustrative purposes only and form no part of the claimed design.

1 Claim, 4 Drawing Sheets
